binding apparatus, and more particularly to a locking mechanism for loose leaf binders which permits full opening of the binder for insertion or removal of loose leaf pages without disengaging the locking mechanism.

UNITED STATES PATENT OFFICE

2,528,866

LOOSE-LEAF BINDER DEVICE

James C. Dawson, Jr., Kirkwood, Mo., assignor to
Loose Leaf Metals Co., St. Louis, Mo., a corpora-
tion of Missouri

Application August 5, 1946, Serial No. 688,473

4 Claims. (Cl. 129—17)

1

The present invention relates generally to loose leaf binders, and more particularly to a locking mechanism for loose leaf binders.

An object of the present invention is to provide a novel locking mechanism for loose leaf binders which in one extreme position maintains the binder in closed relation and in another extreme position permits full opening of the binder for the insertion or removal of loose leaf pages.

Another object is to provide a novel locking mechanism for loose leaf binders which incorporates an intermediate position of parts which permits partial opening of the binder for inspection of the contained sheets without permitting removal thereof.

Another object is to provide a novel locking mechanism for loose leaf binders which automatically locks the binder in closed position upon closing the covers thereof.

Another object is to provide a novel locking mechanism for loose leaf binders which is readily and easily finger pressed for release from its locking positions, but which requires no finger manipulation in assuming an intermediate locking position or a closed locking position after the binder has been fully opened for loose leaf sheet insertion or removal.

Another object is to provide a novel locking mechanism for loose leaf binders which has one part thereof formed integral with the loose leaf binder metal, which simplifies the locking construction.

Other objects are to provide a novel locking mechanism which incorporates a minimum number of parts, which is easy and simple to operate, which is adapted to give long service without maintenance, which is positive in its locking action, which will not slip loose short of actual manipulation of the locking member, and which is both inexpensive to produce and readily fabricated.

Other objects and advantages and the foregoing are apparent from the following description taken with the accompanying drawing, in which:

Fig. 1 is a plan view of a portion of a loose leaf binder metal incorporating a locking mechanism embodying the teachings of the present invention;

Fig. 2 is an end view on a smaller scale of the construction shown in Fig. 1;

Fig. 3 is an enlarged cross-sectional view on the line 3—3 of Fig. 1;

Fig. 4 is a view similar to Fig. 3 but showing the locking mechanism in the intermediate locking position;

Fig. 5 is a view similar to Fig. 3 showing the loose leaf binder metal fully opened to loose leaf page removal or insertion position and the locking mechanism disengaged; and

Fig. 6 is a cross-sectional view on the line 6—6 of Fig. 3.

Referring to the drawing more particularly by reference numerals, 10 indicates generally a loose leaf binder metal which supports at one end a locking mechanism generally designated 12 constructed in accordance with the teachings of the present invention.

The metal 10 includes two body members 14 and 16 which are pivotally mounted on a shaft 18 forming a hinge connection of usual construction. Each body member 14 and 16 has a plurality of longitudinally spaced posts 20 which are secured thereto by welding or otherwise and which are disposed in offset opposed relation, as

is clearly shown in Fig. 1. Each post 20 is formed as a segment of a circle the center of which is the shaft 18. It is to be understood that suitable binder backs or covers are secured to outer walls 22 of the body members 14 and 16 in the usual manner.

The locking mechanism 12 incorporates as one member thereof a portion 24 of end plate 26 of the body member 14. The portion 24 is inwardly offset at 28 from the rest of the end plate 26 and is shaped as is clearly shown in the drawing to include shoulders 30 and 32, a concave edge 34, and convex edges 36 and 38.

The locking mechanism 12 also includes a latch member 40 which is pivotally mounted on a stub shaft 42 journaled in a suitable opening in end plate 44 of the body member 16. The latch member 40 includes a tongue or detent 46, a flange 48 which terminates at one end in a finger piece 50, and a projecting inwardly offset tip portion 52. The tip portion 52 extends into one end of a coiled compression spring 54, the other end of said spring 54 encircling an upstanding metal piece 56 struck up from the body member 16. As is clear from the drawing, the main body of the latch member 40 is disposed against the end plate 44 with the flange 48 (Fig. 1) overlying the edge of the end plate 44.

The latch member 40 and the portion 24 of the end plate 26 are disposed in the same plane, as is clear from Fig. 1, and are so related that the tongue 46 of the former engages the shoulder 30 of the latter when the body members 14 and 16 of the metal 10 are in closed position (Fig. 3).

Further, the tongue 46 of the latch 40 engages

55 the shoulder 32 of the portion 24 in an inter-

mediate position of the body members 14 and 16 (Fig. 4). The latch 40 is entirely free of and removed from connection with the portion 24 when the body members 14 and 16 are in fully opened position, as is shown in Fig. 5.

The operation of the latch is clear from the foregoing description taken with the drawing. Assuming that the metal 10 is in the closed relation of Figs. 1 through 3, which relationship is maintained by the locking mechanism 12, to open the metal 10 to the position of Fig. 5 it is but necessary to press downwardly on the finger piece 50 of the locking mechanism 12, which disengages the tongue 46 from the shoulder 38, permitting the body members 14 and 16 to be manually moved to the position of Fig. 5, the finger pieces 50 being maintained in downwardly pressed position until the tongue 46 has cleared the intermediate shoulder 32. Should it be desired to open the metal 10 to the intermediate position of Fig. 4, the finger piece 50 is released immediately after the tongue 46 has been cleared from engagement with the shoulder 38. To close the metal 10 from either the intermediate position of Fig. 4 or the fully opened position of Fig. 5, it is but necessary to manually fold the body members 14 and 16, for the convex edge of the tongue 46 will ride over the convex edges 38 and 36 of the portion 24, and the tongue 46 will drop down into engagement with the shoulder 38 through the action of the spring 54.

It is manifest that there has been provided a novel locking mechanism for loose leaf binders which fulfills all the objects and advantages sought therefor.

It is to be understood that the foregoing description and the accompanying drawing have been given by way of illustration and example. It is also to be understood that rearrangement of parts, changes in form of elements, and substitution of equivalents, which will be readily apparent to those skilled in the art, are contemplated as within the scope of the present invention, the invention being limited only by the claims which follow.

What is claimed is:

1. In combination, a loose leaf binder metal including a pair of hinged body members, one of said body members having an end plate with a portion formed to provide a shoulder, said portion being inwardly offset, the other body member having an end plate overlapping said shouldered portion and being in the same plane as the remaining portion of the end plate of said one body member, and forming therewith a smooth extension surface when said body members are in closed position, a latch member pivoted on the end plate of said other body member, said latch member being disposed to engage said shoulder when said body members are in closed relation to lock the loose leaf binder metal in closed position, and means for releasing the engagement of the latch member with the shoulder to permit the loose leaf binder metal to be opened.

2. In combination, a loose-leaf binder metal including a pair of hinged body members, one of said body members having an end plate with a portion formed to provide spaced shoulders, said portion being inwardly offset, the other body

member having an end plate overlapping said shoulder portion and being in the same plane as the remaining portion of the end plate of said one body member, and forming therewith a smooth extension surface when said body members are in closed position, a latch member pivoted on the end plate of said other body member, said latch member being disposed to engage one of said shoulders when said body members are in closed relation to lock the loose-leaf binder in closed position, another of said shoulders defining an intermediate position of said metal, and means for releasing the engagement of the latch member with the shoulders to permit the loose-leaf binder metal to be opened.

3. In combination, a loose-leaf binder metal including a pair of hinged body members, one of said body members having an end plate formed integral therewith, said end plate having a portion formed to provide a shoulder, said portion being inwardly offset, the other body member having an end plate overlapping said shouldered portion and being in the same plane as the remaining portion of the end plate of said one body member and forming therewith a smooth extension surface when said body members are in a closed position, a latch member pivoted on the end plate of said other body member, said latch member being disposed to engage said shoulder when said body members are in closed relation so as to lock the loose-leaf binder metal in a closed position, and means for releasing the engagement of the latch member with the shoulder to permit the loose-leaf binder metal to be opened.

4. In combination, a loose-leaf binder metal including a pair of hinged body members, one of said body members having an end plate formed integral therewith, said end plate having a portion formed to provide a shoulder, said portion being inwardly offset, the other body member having an end plate formed integral therewith, said end plate overlapping said shouldered portion and being in the same plane as the remaining portion of the end plate of said one body member and forming therewith a smooth extension surface when said body members are in a closed position, a latch member pivoted on the end plate of said other body member, said latch member being disposed to engage said shoulder when said body members are in closed relation so as to lock the loose-leaf binder metal in a closed position, and means for releasing the engagement of the latch member with the shoulder to permit the loose-leaf binder metal to be opened.
